UNITED STATES PATENT OFFICE

144,441

DESIGN FOR AN EGG LIFTER OR SIMILAR ARTICLE

Albert Joseph Zeleski, Washington, D. C.

Application June 6, 1945, Serial No. 119,941

Term of patent 3½ years

(Cl. D44—4)

To all whom it may concern:

Be it known that I, Albert Joseph Zeleski, a citizen of the United States, residing at Washington, in the District of Columbia, have invented a new, original, and ornamental Design for an Egg Lifter or Similar Article, of which the following is a specification, reference being had to the accompanying drawing, forming part thereof.

Figure 1 is a side elevation view of an egg lifter or similar article, showing my new design.

Figure 2 is a top plan view, and

Figure 3 is an end elevational view thereof.

I claim:

The ornamental design for an egg lifter or similar article, as shown.

ALBERT JOSEPH ZELESKI.
